UNITED STATES PATENT OFFICE.

WILLIAM S. ANDREWS, OF SCHENECTADY, NEW YORK, ASSIGNOR TO THE GENERAL ELECTRIC COMPANY, OF NEW YORK.

ROENTGEN-RAY APPARATUS.

SPECIFICATION forming part of Letters Patent No. 657,378, dated September 4, 1900.

Application filed January 20, 1898. Serial No. 667,198. (No model.)

To all whom it may concern:

Be it known that I, WILLIAM S. ANDREWS, a citizen of the United States, residing at Schenectady, county of Schenectady, State of New York, have invented certain new and useful Improvements in Roentgen-Ray Apparatus, (Case No. 706,) of which the following is a specification.

My invention relates to Roentgen-ray apparatus, and comprises a method and means by virtue of which the vacuum of the tube may be adjusted and maintained continuously at any desired point.

In the practice of my invention I use any form of Crookes tube that contains some chemical—as, for example, caustic potash—preferably placed in a chamber or recess in the tube, which is capable of liberating a gas or vapor when heated. It is well known that when by reason of long-continued use or for any other reason the vacuum becomes too high for the particular purpose to be served the application of heat to this chemical in any way—as, for example, by the passage therethrough of an electric discharge, as shown in patent to Howell, No. 594,156—will liberate a gas or vapor that will reduce the vacuum by an amount depending upon the amount of heat applied. It is the aim of my present invention to make such tubes automatic in their action, and I accomplish this result by taking a connection from some point whose electromotive force is dependent upon the condition of the vacuum in the tube to a condenser or other device which has capacity to absorb and return or dissipate electric energy. The amount of electric energy absorbed and returned or dissipated by such a device will vary with its size, form, and nature and also with the condition of the vacuum in the tube. By passing the current flowing to the said body through a heater surrounding the chemical or through the Howell device or any of its equivalents I am enabled to automatically maintain a certain particular degree of vacuum, and by adjusting the capacity of the body to absorb energy or by adjusting the frequency or voltage of the current supplied to the tube I am able to adjust the vacuum for the production of X-rays having any desired penetrative effects. However, it is not necessary that the electric en-

ergy be returned to the circuit, and any suitable device may be connected with the above-described source of current which will cause the current when the vacuum in the tube is raised to pass through the path in proximity to the gas-yielding body, whether this energy be dispersed in space or to ground or returned to its source by the same path. All such devices under the name of "capacity" devices or condensers are included within the scope of my invention.

In the drawings attached to this specification, Figure 1 is a general view of my improved apparatus in its preferred form. Fig. 2 is a detail view. Fig. 3 is a view of a modification, and Fig. 4 is a view of my improved heating device.

In Fig. 1, A is a source of alternating current feeding a tension-raising transformer T. The secondary of this transformer charges a condenser K, which discharges with an oscillatory discharge through the spark-gap formed between the points P P and the primary of the transformer T' in series. This is the now well-known high-frequency apparatus. The secondary of the transformer T' supplies current to the two terminals B B', to which are connected the two terminals C C' of a tube D. (Here shown as of the double-focus type.) Connected to the tube D and part thereof is the recess or chamber E, with terminal C², in which is placed the chemical F. Connected to the terminal C² by a wire Z is shown a condenser-plate or capacity device G, which may, for example, consist of a sheet of tin-plate suspended in the air by a thread of cotton or other insulating material. The operation of this device I understand to be as follows: An alternating electromotive force is induced in the secondary of the transformer T', which electromotive force causes current to flow in the connections and through the tube in the usual way. Obviously the absolute potential above the earth of any point in this circuit will be alternating in character. Consider, for instance, the point C'. This point will be the seat of an alternating potential, and speaking from the static point of view rather than from the electromagnetic point of view it will be alternately positive and negative. The magnitude of the positive and negative maxima of this po-

tential will depend upon the state of the vacuum in the tube D—the higher the vacuum the greater the maxima. It is therefore evident that when a condenser is used a charging and discharging current may flow from the terminal C' through the recess or chamber E to the terminal C² and to the condenser-plate or capacity device G, thus alternately storing energy in the condenser and returning it minus the losses to the terminal C². It is also evident that within certain limits the higher the vacuum in the tube the greater will be the variation of absolute potential and the maxima of absolute potential at the point C², and the greater will be the magnitude of this current. Suppose that at the start the vacuum of the tube is too high. The charging and discharging current will flow through the chemical F and liberate vapor, which will lower the vacuum. When the vacuum has been sufficiently reduced, current will pass through the tube from H to H', and the static potential at the plate H' will not vary sufficiently to cause any considerable charge and discharge through the branch E to the condenser-plate G, so the liberation of vapor will cease. When the vacuum again rises by the gradual condensation of the liberated vapor in the tube, a charging and discharging current will again pass through the portion E, and the operation will be repeated. For adjusting the vacuum I may obviously adjust either the capacity of the condenser-plate G or the frequency or voltage of the current supplied. For example, I may connect the terminal C² with the wire Z and attach to this wire one large plate G and one or more smaller plates G'. In this way the amount of current flowing through the portion E of the tube, and therefore the amount of vapor liberated by the chemical F, may be varied at will by adding or removing the plates G'; but I find it more convenient in practice to regulate the vacuum for different degrees of penetration by adjusting the length of the spark-gap between the points P P. I accomplish this by mounting the points P P, which are preferably of platinum, in screws Q Q, in a manner shown in detail in Fig. 2, and providing the screws Q Q with insulating-handles R R. The screws fit in brass posts S S, preferably insulated by the sleeves I I. I find that any variation in the length of the spark-gap between the points P P will vary the frequency or electromotive force, or both, of the current in the transformer T'. The result of this is to vary the point at which sufficient current passes into the condenser-plate G to liberate gas from the chemical F, and therefore to vary the point at which the vacuum in the tube is automatically maintained.

Another great advantage of the construction shown in Fig. 1 is that it does not produce a loud noise, which is usual in the operation of apparatus of this character.

In order to provide the draft usually deemed

necessary with such apparatus, I mount the posts S S upon an insulating base-board U, raised by the feet V V and provided with an opening W and a box or cover X, supporting a removable chimney Y. By this arrangement I obtain a simple, cheap, convenient, and nearly-noiseless source of high-frequency currents.

Instead of using the Howell tube, as shown in Fig. 1, I may use the form of tube shown and described in my prior application, Serial No. 639,510, filed June 5, 1897, in which the chemical chamber is surrounded by an electric heater of peculiar construction. (Shown in detail in Fig. 4. This form of tube is shown in Fig. 3, in which it will be seen that the terminal C' is connected to earth through the heater K and the variable spark-gap N. The heater may consist of a tube of glass or other insulating material, in which are placed alternately small pieces of conducting and insulating material, as more fully described in my above-mentioned application, and surrounding the copper tube or sheath L, which serves to distribute the heat. The copper sheath surrounds the portion E of the Crookes tube D, and the terminal C² is absent. One terminal M of the heater is connected to the terminal C' of the tube, while the terminal M' may be connected to a condenser-plate, as is the terminal C² in Fig. 1. The surging currents passing to and fro from the condenser-plate through the heater will then act to generate sufficient heat to liberate the necessary amount of gas from the chemical placed in the end of the tube E.

Obviously I may use the earth in place of the condenser-plate G with either form of tube, and I may, if preferred, regulate the vacuum in the tube by an adjustable spark-gap or any other adjustable resistance suitable for currents of the character used in such apparatus. Such an arrangement I have illustrated in Fig. 3, in which the terminal N' of the heater, which evidently corresponds to the terminal C² in Fig. 1, is connected through the adjustable spark-gap N to earth at O.

When the source of current is an ordinary induction-coil or other comparatively-feeble source, I find it preferable to connect the Howell terminal C², Fig. 1, or the terminal M' of Fig. 3 direct to earth without the use of a spark-gap, unless the induction-coil is one of considerable power, and to regulate the vacuum by adjusting the rheostome.

What I claim as new, and desire to secure by Letters Patent of the United States, is—

1. The method of maintaining a vacuum-tube in operative condition at a predetermined vacuum, which consists in passing current through the tube, and taking a discharge from a point in the circuit to a body capable of absorbing and returning electrical energy, causing said discharge to vary the vacuum in the tube, and varying the discharge in accordance with the vacuum in the tube.

2. The combination with a vacuum-tube of a chamber therein, a chemical adapted to liberate vapor or gas upon the application of heat in said chamber, and a connection whereby a discharge passes from the tube to a body capable of absorbing and returning electrical energy, so as to liberate vapor or gas from said chemical. 70
3. The combination with a vacuum-tube of a chamber therein, a chemical adapted to liberate vapor or gas upon the application of heat in said chamber, a connection whereby a discharge passes from the tube to a body capable of absorbing and returning electrical energy, so as to liberate vapor or gas from said chemical, and means for regulating the amount of said discharge. 75
4. The method of varying the discharge of a part of the current in the circuit of an X-ray apparatus, through a gas-yielding body contained within the tube, which consists in adjusting the frequency of the supply-current. 80
5. The method of varying the capacity of discharge of a part of the current in the circuit of an X-ray apparatus, through a gas-yielding body contained within the tube, which consists in varying the length of the spark-gap in the supply-circuit. 85
6. The combination with a vacuum-tube of a chamber therein, an element adapted to liberate vapor or gas upon the application of heat in said chamber, a body having electric capacity and a connection whereby a surging discharge passes from the tube to said body in proximity to said gas-yielding element. 90
7. The combination of a vacuum-tube having a chamber therein, a chemical adapted to liberate vapor or gas in said chamber, a terminal in said chamber and a connection from the said terminal to earth. 95
8. The combination of a vacuum-tube having a chamber therein, a chemical adapted to liberate vapor or gas in said chamber, a terminal in said chamber, and a connection from the said terminal to earth through an adjustable spark-gap. 100
9. The combination with a source of alternating current, a condenser, an adjustable spark-gap through which the condenser is adapted to discharge a high-frequency electromotive force, and a translating device in series with said spark-gap, the spark-gap terminals being formed of points of refractory material. 105
10. The combination with a source of alternating current, a condenser, an adjustable spark-gap through which a condenser is adapted to discharge a high-frequency electromotive force, and a translating device in series with said spark-gap, the spark-gap terminals being formed of points of refractory material, in combination with a chimney for causing a natural draft across the spark-gap. 110
11. The method of maintaining a desired degree of density in an X-ray tube, which consists in causing an increase in the tube resistance due to the decrease in the density there- 115
- of, to divert current which liberates gas within the tube, and is then absorbed outside the tube. 120
12. Means for maintaining a desired degree of density in an X-ray tube, which comprises a lead from a part of the tube, the electro-motive force of which is dependent upon the degree of tube density, a condenser of the capacity required to maintain the tube density at a desired degree, to which condenser said lead is connected, and a gas-yielding agent within the tube in the path of the current flowing through said lead. 125
13. The method of determining the vacuum at which the tube of an X-ray apparatus shall operate, that is, of varying the operating degree of tube density which consists in varying the capacity of discharge along a path adapted to join the main circuit at one point only and to traverse a gas-yielding body contained within the tube. 130
14. The combination with a Crookes tube, of a condenser electrically connected therewith, to which current flows when the resistance of the tube increases owing to the decrease of tube density, and a gas-yielding body within said tube from which gas is liberated by current flowing to the condenser. 135
15. The combination with a Crookes tube, of a variable condenser electrically connected therewith, and a gas-yielding body within said tube in the path to the condenser. 140
16. The combination with a Crookes tube, of a gas-yielding body therein, and means for diverting a part of the line-current through said body along a path adapted to be connected to the tube at only one point, and then dispersing said part. 145
17. The combination with a Crookes tube, of a gas-yielding body therein, a condenser adapted to receive a discharge of part of the line-current through said body when the vacuum in the tube rises, and means for regulating said discharge. 150
18. The combination with a Crookes tube, of a gas-yielding body therein, a condenser adapted to receive a discharge of part of the line-current when the vacuum in the tube rises, and an adjustable spark-gap in the supply-circuit, whereby said discharge is regulated. 155
19. The combination with a Crookes tube, of a gas-yielding body therein, and means for discharging a part of the line-current in heating relation to said body, and then to earth, when the vacuum in the tube rises. 160
20. The combination with a Crookes tube, of a gas-yielding body therein, a connection from the tube to earth, means for heating said body, and an adjustable spark-gap, both in series in said connection. 165

In witness whereof I have hereunto set my hand this 17th day of January, 1898.

WILLIAM S. ANDREWS.
